UNITED STATES PATENT OFFICE

2,484,514

VENTILATOR WINDOW ASSEMBLY

Guy M. Lane and Harold G. Thunder, Detroit,
Mich., assignors to Motor Products Corporation,
Detroit, Mich., a corporation of New York

Application October 27, 1947, Serial No. 782,266

1 Claim. (Cl. 296—44)

1

This invention relates generally to ventilator windows and refers more particularly to improvements in ventilator window assemblies of the type installed on vehicle bodies.

Vehicle body ventilator window assemblies usually have a main frame divided into two areas or sections by a vertical bar and have a glass panel mounted in the rear section or area for vertical sliding movement. The front area is ordinarily occupied by a ventilator supported on the main frame for swinging movement about a generally vertical axis located between the front and rear edges of the ventilator.

It is customary to make provision for latching the ventilator in its closed position and for this purpose, a latch arm is usually pivoted on the bottom bar of the ventilator frame intermediate the ends of this bar. This location of the latch arm is not the most advantageous for convenience in operation by a person seated in the vehicle immediately adjacent the window, and in any case, the arm usually projects inwardly some distance beyond the window, where it is liable to catch or snag the clothing of the occupant seated adjacent the window.

With the above in view, this invention has as one of its objects to locate the latch arm on the front bar of the ventilator frame in advance of the axis of swinging movement of the ventilator in a position where it may be conveniently manipulated and, at the same time, is out of the way so that the danger of snagging or catching the occupants' clothing on the operating handle is eliminated.

The foregoing as well as other objects will be made more apparent as this description proceeds, especially when considered in connection with the accompanying drawing, wherein:

Figure 1 is a fragmentary elevational view of a ventilator window constructed in accordance with this invention;

Figure 2 is a sectional view taken on the line 2—2 of Figure 1;

Figure 3 is a cross sectional view taken on the line 3—3 of Figure 1; and

Figure 4 is a cross sectional view taken on the line 4—4 of Figure 3.

In Figure 1 of the drawing there is illustrated a part of the vehicle body ventilator window comprising a main frame 10 defining a window opening and divided into two sections or areas by a vertical division bar 11. The rear area or section is adapted to be closed by a glass panel 12 supported in any suitable manner for vertical sliding movement into and out of the area of the

2

window opening in rear of the bar 11. The front section or area of the window opening is occupied by a ventilator 13 supported in the main frame 10 for swinging movement about a generally vertically extending axis 14 located between the front and rear edges of the ventilator.

The ventilator 13 comprises a glass panel 15 and a frame 16 which is usually substantially coextensive with the top, front and bottom edges of the panel 15. The top, front and bottom bars of the ventilator frame 16 are channel-shaped in cross section for receiving the adjacent marginal edge portions of the glass panel 15. As is usual with ventilator windows of the above general type, the rear swinging edge of the panel 15 is adapted to abut a weather-strip (not shown) on the vertical division bar 11 when the ventilator is in its closed position. Also, in accordance with conventional practice, a flexible weather-strip 17 is secured to the main frame 10 around the ventilator 13 and is shaped to establish a weather-tight seal between the ventilator and main frame when the ventilator is in its closed position.

In many types of ventilator window constructions, the front bar 18 of the ventilator frame 16 and the corresponding bar of the main frame 10 are inclined rearwardly in the manner indicated in Figure 1 of the drawing. The front bar 18 is pivoted intermediate the ends thereof to the adjacent bar of the main frame by a pivot 19 having its axis coincident with the axis 14 and the bottom bar of the ventilator frame is pivoted to the bottom bar of the main frame by a pivot 20 having its axis also coincident with the axis 14. The particular construction of the pivots employed forms no part of this invention, and therefore, need not be described in detail herein. It will suffice to point out that the pivots are such as to permit swinging movement of the ventilator 13 about the axis 14, and that the pivot 20 is of the friction type adapted to hold the ventilator in any one of its selected adjusted positions.

The ventilator 13 is secured in its closed position by a latch 21 comprising a latch arm 22 and a keeper or cam plate 23. The arm 22 is rotatably supported at the inner side of the ventilator 13 on the front frame bar 18 in advance of the axis of swinging movement 14. For accomplishing this result, a bracket 24 is provided having a part 25 extending into the channel of the ventilator frame bar 18 and secured to the base of the channel by a suitable rivet 26 in the manner clearly indicated in Figure 3 of the drawing. The bracket 24 also has a cylindrical part 27 which extends laterally inwardly from the

part 25 through a suitable slot formed in the inner flange of the channel-shaped frame bar 18.

The latch arm 22 is provided with a hub 28 rotatably supported on the cylindrical part 27 of the bracket 24, and is secured to the latter by a threaded stud 29. The stud 29 extends coaxially with respect to the cylindrical part 27 and the end of the hub 28 is apertured to freely receive the stud. Thus while the stud 29 secures the latch arm to the bracket 24, it nevertheless permits rotation of the arm 22 relative to the bracket 24.

In addition to the hub 28, the latch arm 22 is also formed with an operating handle 30 and a projection 31 which extends from the hub 28 at right angles to the operating handle 30. The arrangement is such that when the ventilator 13 is in its closed position and the latch arm 22 is rotated to the position shown in Figure 1 wherein the operating handle overlies the ventilating frame bar 18, the projection 31 engages the cam plane 23 and secures the ventilator in its closed position. In this connection attention is again directed to Figure 3 of the drawing, wherein it will be noted that the cam plate or keeper 23 is secured to the base of the channel-shaped front bar on the main frame 10, and has a cam portion which extends inwardly to a position for engagement with the projection 31 on the latch arm 22.

The extent of rotation of the latch arm to its operative and released positions is determined by lugs 33 and 34 respectively secured to the bracket 24 and latch arm 22. The lug 33 extends axially inwardly from the cylindrical part 27 on the bracket, and the lug 34 extends radially inwardly from the inner surface of the hub 28 on the latch arm. The location of the lugs is such as to locate the arm 22 in its latched position with the operating handle overlying the inner side of the front frame bar 18 on the ventilator. 40

Thus the operating handle is not only rendered less conspicuous, but is located in a position where it is less likely to catch or snag on the clothing of a person seated immediately adjacent the window.

What we claim as our invention is:

A ventilator window comprising a main frame, a ventilator supported in the main frame for swinging movement about an up and down axis 10 located between the front and rear edges of the ventilator, a frame for the ventilator having a bottom bar and having a rearwardly opening channel shaped front bar inclined rearwardly from the bottom bar, a bracket having a part 15 positioned within the channel of the front ventilator frame bar and secured to the base of said channel intermediate the ends of the front ventilator frame bar, said bracket having another part extending laterally inwardly with respect to the ventilator through an opening in the inner flange of the channel shaped front bar, a latch arm 20 rotatably supported on the inwardly extending part, and a keeper on the main frame adjacent the latch arm and engageable with said arm upon 25 rotation of the latter to one position for securing the ventilator in its closed position in said main frame.
